(57)

CLAIM

The ornamental design for a surgical cart, as shown and described.

DESCRIPTION

The patent or application file contains at least one drawing executed in color. Copies of this patent or patent application publication with color drawing(s) will be provided by the Office upon request and payment of the necessary fee.

1. Surgical cart

1.1 : Perspective

1.2 : Perspective

1.3 : Front

1.4 : Back

1.5 : Left

1.6 : Right

1.7 : Top

The product is used to provide mobility, guiding, positioning and stable support for interventional surgery robots.

1 Claim, 7 Drawing Sheets
